PERCUSSIVE TOOL

Application filed July 27, 1929. Serial No. 381,504.

This invention relates to percussive tools, and more particularly to percussive tools employing differential hammer pistons for actuating the working implement and in which the hammer piston or a portion thereof serves to control the distribution of the pressure fluid to the piston chamber.

One object of the invention is to obtain a maximum amount of work from the tool with a minimum expenditure of pressure fluid.

Another object is to obtain a rapid action of the percussive element of the tool, and still another object is to render the tool free from objectionable shocks and vibration.

Other objects will be in part obvious and in part pointed out hereinafter.

In the drawings illustrating one form which the invention may assume in practice,

Figure 1 is a sectional elevation of a percussive tool constructed in accordance with the practice of the invention and showing the piston in a position to begin its forward stroke, and

Figure 2 is a view similar to Figure 1 showing the piston about to begin its rearward stroke.

Referring more particularly to the drawings, A represents the cylinder of a percussive tool and B a piston chamber therein comprising in this instance an enlarged bore C and a reduced or smaller bore D. A closure is provided for the front end of the piston chamber B in the form of a front cylinder washer E which also serves as a guide for an anvil block F adapted to act against a working implement G guided by a front head H at the forward end of the cylinder. On the rearward end of the cylinder A is seated a plate J which in turn serves as a seat for a back head K.

The parts comprising the casing of the tool, such as the cylinder A, the front head H, the plate J and the back head K may be secured relatively to each other in any suitable manner, as for instance, by the usual side bolts (not shown).

In accordance with the present invention the piston chamber B is provided with a piston L comprising in this instance a stem O

chamber and a head P slideable in the enlarged bore C of the piston chamber B. On the rearward end of the stem O is a pressure surface Q constantly exposed to pressure fluid tending to actuate the piston L forwardly against the anvil block F and at the forward end of the head P is an actuating surface R against which pressure fluid may intermittently act for returning the piston. An end surface S on the rearward end of the head P is constantly exposed to atmospheric pressure through a vent T leading from the rearward end of the enlarged bore C of the piston chamber to the atmosphere.

In the back head K is disposed a throttle valve U having a central chamber V which may be in constant communication with a source of pressure fluid supply, and in the side of the throttle valve U is a port W adapted to register with a passage X in the back head and communicating with a passage Y in the plate J and opening into the rearward end of the piston chamber B.

In the construction shown the piston chamber B is provided with a free exhaust port Z which is so located that a portion of the fluid from only the front end of the piston chamber B will be exhausted therethrough to the atmosphere.

In the present instance the stem O of the piston L also serves to control an initial admission of pressure fluid to the front end of the piston chamber B through an inlet passage b which leads to the front end of the enlarged bore C of the piston chamber and communicates with the reduced bore D at a point near the forward end thereof through a port c. The port c is preferably so arranged that it will be uncovered by the stem O of the piston at about the time the piston delivers its blow against the anvil block F.

Additional means are provided for continuing the supply of pressure fluid to the front end of the piston chamber B after the port c has again been covered by the piston L on the return stroke of the piston. To this end the plate J is provided with a valve chamber d to accommodate a differential valve e comprising a head f and a stem g. The portion of the valve chamber wherein the stem g of

the valve is adapted to slide opens directly into the rearward end of the reduced bore D of the piston chamber so that an actuating surface *h* on the end of the stem *g* will be 5 constantly exposed to pressure fluid tending to move the valve *e* into its closed position.

On the free extremity of the head *f* of the valve is an actuating surface *j* of greater area than the actuating surface *h* and said actuating surface *j* is exposed to pressure fluid flowing through the inlet passage *b* which, as will be observed, communicates with the enlarged portion of the valve chamber *d* for moving the valve *e* into the closed position.

15 As may be readily observed from the foregoing description, the period of time which elapses between the opening of the port *c* and its closing by the piston *L* is of short duration so that therefore an insufficient amount 20 of pressure fluid would be supplied to the front end of the piston chamber *B* to fully retract the piston *L* against the opposing pressure acting against the pressure surface *Q*. In order therefore to insure an ample 25 supply of pressure fluid to the front end of the piston chamber for returning the piston, the tool is provided with a supply passage *k* which leads from a point near the rearward end of the reduced bore *D* of the piston chamber *B* to the rearward end of the valve chamber *d*, so that in the open position of the valve 30 pressure fluid may flow directly from the rearward end of the piston chamber *B* and through the corresponding end of the valve chamber *d* into the inlet passage *b*. Communication 35 between the supply passage *k* and the inlet passage *b* is in this instance controlled by the head *f* of the valve, the arrangement being such that the actuating surface *j* will seat directly over the inlet opening 40 of the inlet passage *b*.

As has been previously intimated, only a portion of the pressure fluid utilized for actuating the piston *L* rearwardly is exhausted to the atmosphere through the exhaust port *Z*. In order to completely evacuate the front end of the piston chamber *B* preliminary to the forward stroke of the piston *L* the cylinder *A* is provided with an 45 exhaust passage *o* which leads from the forward end of the enlarged bore *C* of the piston chamber to the enlarged portion of the valve chamber *d*, and the valve chamber *d* is suitably enlarged as at *p* to afford communication 50 between the exhaust passage *o* and an atmospheric port *q* in the closed position of the valve *e*.

The operation of the device is as follows: With the parts in the position illustrated in 55 Figure 1, pressure fluid flowing from the throttle valve *U* through the passages *X* and *Y* will enter the rearward end of the piston chamber *B* to act against the pressure surface *Q* for driving the piston *L* forwardly 60 against the anvil block *F*. Pressure fluid

thus admitted into the piston chamber will act against the actuating surface *h* of the valve *e* and hold the valve closed to prevent communication between the supply passage *k* and the inlet passage *b*. In this position of the valve communication will be established between the exhaust passage *o* and the atmospheric vent *q* so that the air in the front end of the piston chamber will be expelled to the atmosphere through these channels. The piston *L* will therefore not be required to act against resistance and, in consequence, a heavy blow will be delivered to the working implement through the medium of the anvil block *F*.

As the piston *L* approaches the forward limiting position of its travel the stem *O* of the piston will uncover the port *c* and pressure fluid will then flow into the inlet passage *b* to the front end of the piston chamber to immediately start the piston *L* on its return stroke. At the same time pressure fluid will flow to the rearward end of the valve chamber *d* to act against the actuating surface *j*. In this way the valve *e* will be moved into the open position illustrated in Figure 2 and pressure fluid will then flow from the reduced bore *D* through the supply passage *k* and over the actuating surface *j* of the valve and through the inlet passage *b* into the front end of the piston chamber to drive the piston *L* to its rearmost position. This position of the piston may be only such that the exhaust port *Z* will be only momentarily opened, but the time during which it is uncovered will be sufficient to lower the pressure in the front end of the piston chamber and therefore also that pressure acting against the actuating surface *j* to such a value that the pressure acting against the actuating surface *h* of the valve will predominate, it being understood of course that in this same position of the piston *L* the supply passage *k* will have been closed by the stem *O* of the piston. The valve *e* will then be moved to the closed position so that the front end of the piston chamber will be open to the atmosphere through the exhaust passage *o*, the valve chamber *d* and the atmospheric vent *q*.

Throughout the operation of the tool the end surface *S* of the piston head *P* will be constantly exposed to atmospheric pressure through the vent *T* and only pressures acting against the pressure surfaces *Q* and *R* will be instrumental in actuating the piston *L*.

The present invention has been found to be unusually efficient in the matter of pressure fluid consumption. It is capable of operating at an extremely high rate of speed and also of delivering a heavy blow to the working implement. This is due largely to the facts that the pressure fluid utilized for actuating the piston forwardly on its working stroke acts only expansively and that only the pressure fluid used for impelling the piston in one

direction is exhausted from the piston chamber, and to the further fact that during the forward stroke of the piston L the space forwardly of the pressure surface R is completely vented so that the forward movement of the piston L is in no wise opposed. Another feature of the present invention and one which is particularly desirable in hand held percussive tools is the absence of vibration or shock during the return movement of the piston. This is due to the small differential between the pressure surfaces Q and R so that the pressure for actuating the piston L rearwardly need be only slightly greater than that opposing the rearward movement of the piston.

We claim:

1. A fluid actuated percussive tool, comprising a cylinder having an enlarged bore and a smaller bore to form a piston chamber, a piston in the piston chamber having a head and a stem, a pressure surface on the stem constantly exposed to pressure fluid for driving the piston forwardly, a pressure surface on the front end of the head intermittently exposed to pressure fluid for returning the piston, a valve chamber, a valve in the valve chamber having differential actuating surfaces, the smaller of which is constantly exposed to pressure fluid tending to close the valve and the actuating surface of larger area being intermittently exposed to pressure fluid for opening the valve, a supply passage leading from the smaller bore to the valve chamber and controlled by the stem, an inlet passage leading from the valve chamber to the front end of the enlarged bore and communicating with the supply passage in the open position of the valve, a port affording communication between the smaller bore and the inlet passage and controlled by the stem to expose the last said pressure surface to pressure fluid for starting the piston on its return stroke and to simultaneously open the valve, thus permitting the flow of pressure fluid from the smaller bore through the supply passage and the inlet passage into the front end of the enlarged bore to complete the rearward stroke of the piston, an exhaust port in the cylinder to exhaust a portion of the fluid from the front end of the piston chamber, and an exhaust passage in the cylinder controlled by the valve for completing the exhaust of fluid from the same end of the piston chamber.

2. A fluid actuated percussive tool, comprising a cylinder having a piston chamber, a differential piston in the piston chamber having only two end pressure surfaces, one of said surfaces being constantly exposed to pressure fluid for driving the piston forwardly and the other surface being intermittently exposed to pressure fluid for driving the piston rearwardly, a surface on the piston intermediate the pressure surfaces and constant-

ly exposed to atmospheric pressure, a valve chamber, a valve therein constantly exposed to pressure fluid in the piston chamber tending to close the valve, an inlet passage in the cylinder controlled by the piston to intermittently expose the valve to pressure fluid for opening the valve, and supplying pressure fluid through the inlet passage independently of the valve to the front end of the piston for starting said piston on its return stroke, a supply passage controlled by the piston leading from the rear end of the piston chamber to the valve chamber and communicating with the inlet passage in the open position of the valve, thus permitting the flow of pressure fluid from the rear end of the piston chamber to the front end thereof to complete the rearward stroke of the piston, and ports and passages in the cylinder controlled by the piston and the valve for exhausting fluid alternately from only the front end of the piston chamber.

In testimony whereof we have signed this specification.
